Primary Examiner — Mojtaba Tehrani

CLAIM

The ornamental design for a grooving insert for machine tools for metalworking, as shown and described.

DESCRIPTION

1. Grooving insert for machine tools for metalworking

1.1 : Perspective

1.2 : Front

1.3 : Back

1.4 : Top

1.5 : Bottom

1.6 : Left

1.7 : Right

1 Claim, 7 Drawing Sheets
